PROCESS OF WEAVING ELASTIC WEBBING

Filed Aug. 24, 1922

Inventor:
Harold St. J. Guild,
by J. S. McCready
his Atty.

UNITED STATES PATENT OFFICE.

HAROLD ST. J. GUILD, OF JAMAICA PLAIN, MASSACHUSETTS.

PROCESS OF WEAVING ELASTIC WEBBING.

Application filed August 24, 1922. Serial No. 584,003.

To all whom it may concern:

Be it known that I, HAROLD ST. J. GUILD, a citizen of the United States, residing at Jamaica Plain, in the county of Suffolk and 5 State of Massachusetts, have invented certain new and useful Improvements in Processes of Weaving Elastic Webbing, of which the following is a specification.

This invention relates to the manufacture 10 of elastic webbing of the character used in suspenders and the like. The invention is particularly concerned with single ply webbing of this character.

It has been customary heretofore to 15 manufacture single ply elastic webbing by using a single shuttle for each web. This process necessarily is relatively slow, and it is the chief object of the present invention to devise a process of manufacturing elastic 20 webbing which will be faster and more economical than the processes heretofore practiced.

The nature of the invention will be readily 25 understood from the following description when read in connection with the accompanying drawings, and the novel features will be particularly pointed out in the appended claims.

In the drawings, 30 Figure 1 is a diagram showing the shed and shuttle arrangement preferably used in manufacturing webbing in accordance with the present invention;

Fig. 2 is a diagram showing the character 35 of the weave at one edge of a piece of webbing embodying the invention; and

Fig. 3 is a perspective diagrammatic view showing the character of the weave at one edge of the fabric.

Referring to the drawings, Fig. 1 illustrates 40 an arrangement which may conveniently be used in practicing the present invention with the aid of a narrow ware loom of the usual construction. As here illustrated, the warp threads and the strands 45 of rubber are arranged to form two sheds, one above the other, the strands of rubber occupying an intermediate position and forming the bottom of the upper shed and 50 the top of the lower shed. These strands of rubber, commonly called "rubbers," are drawn from a beam 3. The warp threads may be handled in any convenient manner. In the arrangement shown the warp threads

for the body of the fabric are guided on 55 the rolls 4 and 5, and the marginal warps and the gut threads, if such are used, on the roll 6. The breast roll is indicated at 7.

Upper and lower shuttles 1 and 2 run 60 in the upper and lower sheds, respectively, and they preferably are projected through the sheds simultaneously in the same direction, although they may, if desired, be propelled in opposite directions simultaneously. The harness motion will depend upon the 65 pattern which it is desired to weave, as will be obvious to those skilled in this art. The strands of rubber remain stationary.

With this arrangement a double length 70 of filling is inserted at each pick. The two shuttles 1 and 2 can be operated as rapidly as can a single shuttle, and consequently twice as much filling can be laid with this process as in the prior processes of weaving single ply fabric. This webbing, therefore, can be produced at substantially twice 75 the rate that single ply webbing can be woven by the processes heretofore practiced. A further advantage of this arrangement as compared with prior processes, is that 80 no up and down movement of the strands of rubber is required, so that the friction on these strands and on the warp threads is substantially reduced.

At the edges of the fabric a tubular selvage 85 is woven to enclose the edge rubbers. This feature of the invention will be readily understood from an inspection of Fig. 2, which shows a cross sectional diagram at one edge of the fabric during the process 90 of weaving, the dotted line X—Y separating the body of the goods at the right from the edge or margin thereof at the left. This diagram assumes that the weave in the body 95 of the fabric, so far as here indicated, is plain, the threads forming the top of the upper shed during one pick being designated at A, while those at the bottom of the lower shed at this instant are designated at C. The strands of rubber in the body of the 100 web are indicated at D.

The edge rubbers D' preferably are at 105 least twice as heavy as the body rubbers D, or an equivalent effect is produced by using two strands of rubber in each edge, each strand being of substantially the same weight as those used in the body of the goods. The weight of the rubber threads

used in the margin may, of course, be varied to suit the requirements of the particular piece of goods being woven, but in any event it should be substantially greater than the rubber used at any given point in the body of the goods. The marginal warp threads F and G are manipulated by the harnesses in the manner readily understood by those skilled in this art to cooperate with the filling thread P, carried by the upper shuttle, to form a single ply fabric, as will be evident from an inspection of Fig. 2. The two sections of this diagram show successive picks. The threads F and G work through the upper shed only, as will be obvious from Fig. 2. At the same time the warp thread B, which may be designated as a tie thread, and which works, one pick up and one pick down, through both sheds outside the threads F and G, is woven in with both filling threads P and Q and, consequently, ties the outer edge of this single ply marginal fabric to the lower filling thread and, hence, to the body of the fabric. A greater tension is used on the lower thread Q than on the upper thread P and, due to this difference in tension, the lower thread pulls the outer edge of this single ply marginal fabric backwardly around the edge rubbers D'-D' where it substantially encircles or encloses the edge rubbers. This action will be clearly understood from an inspection of Fig. 3 which illustrates the manner in which the upper and lower filling threads P and Q are united by the tie thread B, and also shows how the greater tension on the lower filling thread Q pulls the outer edge of the single ply margin around the edge rubbers D'. In this figure, and also in Fig. 2, the size of the threads and the spaces between them have, of course, been exaggerated, as will readily be understood. The increased weight of rubber used in the margin is sufficient to contract this tubular selvage to the same degree that the body fabric is contracted by the body rubbers D, so that the web lies flat and even when it is completed. The same weave is used at the opposite selvage.

This invention is especially applicable to the weaving of lisle webbing which is much used in the lighter weight suspenders, and because of the increased production afforded by this process with substantially the same equipment ordinarily used for single ply goods, it effects a substantial economy in the manufacture of these light weight webbings. While there may be some question technically as to the accuracy in designating the goods described as "single ply goods," still goods of this character are known in the trade by this term and also as "lisle" webbing.

It will be understood that no attempt has

been made to describe the various patterns or weaves that can be used in manufacturing webbing according to this invention, the foregoing description being intended as a disclosure of the more essential features of the invention. Additional threads can, of course, be used for the purpose of producing patterns. A further advantage of this process is that yarn or thread of different characteristics may be used in the two shuttles so that the face and back of the goods will present substantially different appearances. For instance, silk thread may be run in the face shuttle and cotton thread in the back shuttle. These and other weaving expedients will, however, be obvious to those skilled in this art.

This process may also be used with the same advantages in the weaving of non-elastic webbings used for straps, belts and the like, where central warps, frequently referred to as "padding warps," or "gut warps," are used in place of the rubber strands, and are handled in the same way. Consequently, the reference in the foregoing description and in the appended claims to strands of rubber, should be understood, where the context permits, to include gut warps of the character just mentioned, it being understood that the statements above made as to the increased weight of rubber in the margins of the goods would not apply in the case of these non-elastic fabrics.

Having thus described my invention, what I desire to claim as new is:

1. That improvement in the process of weaving narrow elastic webbing which consists in arranging warp threads and strands of rubber to form two sheds, one above the other, with the strands of rubber forming the top of the lower shed and the bottom of the upper shed, inserting two filling threads in said sheds simultaneously at each pick with one thread in each shed, manipulating the warp threads throughout the greater part of both sheds to form, with said filling threads, a single ply fabric of the desired pattern, manipulating the edge warps to cooperate with one only of said filling threads to weave a single ply margin at each selvage edge outside the edge strands of rubber, manipulating a tie thread at each selvage edge to tie both filling threads together, and applying greater tension to the second filling thread than to the filling thread in said single ply margins whereby the second filling thread will act through said tie thread to pull said single ply margins around the edge strands of rubber.

2. That improvement in the process of weaving narrow elastic webbing which consists in arranging warp threads and strands of rubber to form two sheds, one above the other, with the strands of rubber forming

the top of the lower shed and the bottom of the upper shed, inserting two filling threads in said sheds simultaneously at each pick with one thread in each shed, manipulating the warp threads between picks to cooperate with said filling threads to produce a single ply fabric of the desired pat-

tern, using substantially heavier strands of rubber in each selvage edge than at any point in the body of the fabric, and manipulating the edge warps to form, with said filling, a tubular woven selvage enclosing the edge strands of rubber. ¹⁰

HAROLD ST. J. GUILD.
